UNITED STATES PATENT OFFICE.

SAM WATSON ROBBINS, OF BRISTOL, ENGLAND.

WRINGER FOR MOPS, FLOOR-CLOTHS, AND THE LIKE.

1,391,408.

Specification of Letters Patent. Patented Sept. 20, 1921.

Application filed October 6, 1920. Serial No. 415,086.

To all whom it may concern:

Be it known that I, SAM WATSON ROBBINS, of Horfield, Bristol, in the county of the same city, England, a subject of the 5 King of Great Britain and Ireland, have invented certain new and useful Improvements in Wringers for Mops, Floor-Cloths, and the like, of which the following is a specification.

10 This invention relates to wringers for wringing mops, floor cloths and the like of the type in which the wringing is effected by squeezing the mops, floor cloths and the like between two rollers and by drawing the 15 articles from between the said rollers.

The object of this invention is to provide an improved device of this kind.

A wringer made in accordance with this invention comprises a water-tight vessel, 20 wringing rollers mounted on spindles transversely disposed in said vessel, one of said rollers being fixed and the other capable of traveling lengthwise of the vessel, the spindle of the traveling roller operating in slots 25 formed in or mounted on the vessel, means for bringing the traveling roller up against the fixed roller by foot pressure, and means for keeping the rollers normally apart.

Referring to the accompanying drawings, 30 Figure 1 is a side elevation of a wringer made in accordance with this invention. Fig. 2 is a front view and Fig. 3 a plan. Fig. 4 shows, in side elevation, a modified construction. Fig. 5 is a side elevation of a 35 further modification. Fig. 6 is a front view, and Fig. 7 is a plan.

In Figs. 1, 2 and 3 are shown an apparatus comprising a box or bucket 1 adapted to hold water and provided with two rollers 40 2 and 3 which are free to rotate about their respective spindles 4 and 5. The spindle 4 of the roller 2 is slidable lengthwise of the vessel in slots 6 provided in the sides of the box. The spindle 5 of the roller 3 can not 45 so travel. Normally, the roller 2 is held at the extremity of its outward travel by springs 7 attached at one end to the spindle 4 and anchored at the other end to pins 8 or the like.

50 The spindle 4 of the roller 2 is connected to angle brackets 9 by flexible cords, wires or the like 10 which are conducted over the pulleys 11 rotatably mounted for rotation in brackets 12 fixed to the vessel 1.

55 The angle brackets 9 are fixed to a pedal

lid 13 which is attached by hinges 14 to the vessel 1 which is provided with handles 15.

In using the appliance, the mop, floor cloth or other article to be wrung, is placed 60 and held between the rollers 2 and 3. The pedal 13 is then tilted down by foot pressure applied thereto. This action causes the roller 2 to travel toward the roller 3 and expands the springs 7. The mop, floor cloth 65 or other article is accordingly squeezed between the rollers and is wrung out by being pulled up from between the compressing rollers, the expressed water falling into the vessel 1. On the foot pressure being relaxed from the pedal, the pedal is tilted up 70 by the contracting action of the springs 7 and the roller 2 is also thereby returned to normal position at the outer end of the slots 6.

In the modification illustrated at Fig. 4 the front roller 17 is, as in the case above described, slidable lengthwise of the vessel. The roller 17^a is non-slidable. The spindle 16 of the roller 17, which slides in the 80 slots 18, is connected to springs 19 which are anchored at the outer ends to pins or other fastenings provided in the sides of the vessel. The spindle 16 is pivotally connected to an arm 20 which is also pivotally connected to a pin 21 to which are also pivotally connected arms 22 and 23. The arm 22 is pivotally mounted on a pin 24 fixed in the side of the vessel. The arm 23 is pivoted on a rod 25 carried by the pedal 26 which 85 latter is hinged at 27 to the vessel.

It is to be understood that like mechanism is arranged at both sides of the vessel.

The operation of wringing is, as in the case first above described, performed by applying foot pressure to the pedal 26 and withdrawing the article being wrung from between the rollers 17 and 17^a. The springs 19 return the roller 17 outward to normal 90 position.

At Figs. 5, 6 and 7 is illustrated a further modification. In this arrangement the rear roller 29 is slidable, and the front roller 33 is non-slidable. To the spindle 28 of the 100 slidable roller 29 are connected the springs 30 anchored at points 31 to the vessel. The springs are not external. They are contained within recesses provided for them in the wall of the vessel. The spindle 28 of the roller 29 is pivotally connected by arms 105 110

34 to a bar 35 which is carried by the pedal lid 36 which is hinged to the vessel by hinges 37.

Instead of having the springs by which 5 the slideable roller is returned and the pedal lid elevated arranged at or in the sides of the vessel, the pedal lid may be acted upon by springs directly applied thereto, or the hinges of the lid may be spring-influenced, 10 the requisite connection being established between the pedal and the slideable roller.

The vessel may be of any suitable shape and dimensions. It may be made of galvanized iron, aluminium or other suitable 15 metal.

Any convenient form of handle or handles may be fitted to the appliance as may be desired.

Instead of being rotatable about their 20 spindles, the rollers, or either of them, may be secured on their respective spindles so as to rotate therewith and in cases where the slideable roller is secured on its spindle, the connection of the springs in relation to the

roller is such as to obviate winding of the 25 springs on the spindle.

What I claim and desire to secure by Letters Patent is:—

A wringer, comprising a receptacle, a pedal pivotally secured to the upper edge of 30 said receptacle and adapted to swing inwardly over the receptacle when depressed, thereby to form a cover for said receptacle, a pair of rollers mounted for rotation within the receptacle, one of said rollers being 35 slideable toward the other, a toggle connection between said pedal and slideable roller for sliding the same in one direction, and a pair of springs disposed outside of the receptacle and automatically operable on 40 removal of pressure from said pedal for sliding the roller in the opposite direction and simultaneously returning the pedal to its initial position.

In testimony whereof I have signed my 45 name to this specification.

SAM WATSON ROBBINS.
